SIGNAL TRANSLATING APPARATUS

Emile C. Guedon, Audubon, N. J., assignor to Radio Corporation of America, a corporation of Delaware

Application November 30, 1937, Serial No. 177,293

17 Claims. (Cl. 179—100.41)

This invention relates to signal translating apparatus, and more particularly to a pick-up device of the electromagnetic type for use in reproducing sound from phonograph records.

5 In pick-up devices of the type mentioned, the armature is mounted to vibrate between a pair of associated pole pieces in response to variations in contour of the recorded groove on the record. The armature normally stands midway between 10 the pole pieces in its unexcited condition but is deflected from its central position as the record passes under the needle carried by the armature, thereby generating signal voltages in a winding or coil which surrounds the armature and which 15 is in circuit with suitable amplifying means and a loudspeaker. In order to increase the range of operation of the pick-up, it has been proposed to increase the size of the winding about the armature. This, however, also necessitates increasing the length of the armature so that its 20 inertia is increased and its frequency range correspondingly lowered. It has also been proposed to increase the size of the magnetic structure which supplies the magnetic field in which the 25 active end of the armature operates, but this, too, has a disadvantage in that the magnetic structure cannot be increased too much without making the device too heavy and too cumbersome for proper operation.

30 The primary object of my present invention is to provide an improved electromagnetic pick-up device having a greater range of operation than those heretofore known and in which the disadvantages noted heretofore are not present.

35 More particularly, it is an object of my present invention to provide an improved pick-up device of the type set forth which will have a high output regardless of its impedance.

Another object of my invention is to provide an 40 improved pick-up device as aforesaid which has abundant winding space for the armature winding but which does not require a long armature.

Still another object of my invention is to provide an improved electromagnetic pick-up device 45 which may be operated as a low impedance device, an intermediate impedance device, or a very high impedance device, and which can be changed from one to another with great facility.

A further object of my present invention is to 50 provide an improved electromagnetic pick-up in which the air gap can be readily and accurately adjusted to provide the desired flux density.

It is also an object of this invention to provide 55 an improved pick-up device as aforesaid which is very simple in construction and which is highly

efficient in operation over a very wide range in the audio spectrum.

In accordance with my present invention, I 5 form the armature of two portions one of which is stationary and the other of which is pivotally 10 carried by the stationary portion for cooperation with the record. The stationary armature is surrounded by a relatively large high impedance winding, while the movable armature is surrounded by a relatively small, low impedance 15 winding, and the signal voltages generated by the two coils in response to vibration of the movable armature may be either used separately or combined. Both armatures are terminated in suitable 20 air gaps, and the movable armature is made short so that it will have a very low moment of inertia about its vibratory axis and therefore will give high fidelity reproduction. The magnetic structure is so arranged that the pole pieces 25 for each of the armatures may be readily moved either toward or away from each other and then fixed in adjusted position whereby the air gaps 30 can be easily adjusted.

The novel features that I consider characteristic 25 of my invention are set forth with particularity in the appended claims. The invention itself, however, both as to its organization and method of operation, together with additional objects and advantages thereof, will best be understood from the following description of a 30 specific embodiment thereof, when read in connection with the accompanying drawing, in which

Figure 1 is a top plan view of a pick-up device 35 according to my present invention, with the cover removed.

Figure 2 is a sectional view thereof taken on the line 2—2 of Fig. 1.

Figure 3 is a sectional view taken on the line 3—3 of Fig. 2, and

Figure 4 is a wiring diagram showing how the 40 two windings of the pick-up device may be connected.

Referring more particularly to the drawing, wherein similar reference numerals designate corresponding parts throughout, there is shown 45 a die cast supporting member 1 of non-magnetic material provided with a bushing 3 by means of which the device may be mounted on a suitable supporting arm (not shown) and having also a forwardly extending plate member 5 terminating 50 in a needle guide 7 having an opening or slot 9 through which a needle may be inserted for a purpose presently to be described. Secured to the plate 5 by the screws 11 are a pair of oppositely directed blocks 13 of magnetic material 55

to which a permanent magnet 15 is spot welded or otherwise suitably secured, the blocks 13 supporting at their tops a pair of cooperating pole pieces 17 and at their bottoms another pair of 5 cooperating pole pieces 19. The pole pieces 17 lie in the same plane and are physically separated from each other to provide an air gap 21 therebetween, while the pole pieces 19, also both lying in a single plane, are physically separated from 10 each other to provide an air gap 23 therebetween. Each of the pole pieces is provided with a transverse slot 25 in which is received the flat head of a screw 27, each in turn threadedly received in the blocks 13 for axial movement in a plane 15 parallel to the planes of the two sets of pole pieces. It will be obvious that adjustment of the screws 27 in their threaded openings will cause the pole pieces of the respective pairs to move either toward or away from each other 20 whereby to vary the size of the air gaps 21 and 23. Each of the pole pieces 17 and 19 is also provided with an opening 29 through which extends a locking screw 31 threaded in the blocks 13 and serving to lock the respective pole pieces in any 25 position of adjustment as determined by the screws 27. The openings 29 are made longer than the diameters of the screws 31 to permit a substantial degree of adjustment of the several pole pieces longitudinally.

30 It will be noted that the pole pieces 17 are located to one side of the plate 5 and the pole pieces 19 are located on the other side of the plate 5. Fixed to the plate 5, substantially centrally thereof, is a stationary armature 33 having the major portion thereof extending above the plate 5 and terminating in the air gap 21. The armature 33 also extends a short distance below the plate 5 and pivotally carries an armature shaft 35 on which is formed a downwardly extending, short armature 37 the active end of which terminates in the air gap 23. A spring 39, formed of piano wire or the like and suitably secured to the blocks 13, as by a pair of clamps 40, and to the armature shaft 35, tends constantly 40 to maintain the armature 37 centered in the air gap 23. The armature shaft 35 may be further supported in a bearing 41 carried by the needle guide 7 and is provided with a needle socket 43 in which a needle (not shown) may be secured by a screw 45. The other end of the 45 armature shaft 35 may be embedded within a suitable damping member 47 secured to the frame member 1, as by a screw 49. The damping member 47 may be of the type disclosed in 50 the Kendall Patent No. 2,092,884.

55 Within the space between the plate 5 and the pole pieces 17, and surrounding the major portion of the stationary armature 33, is a winding or coil 51 having a high impedance. In the space 60 between the plate 5 and the lower pole pieces 19, and surrounding the armature 37, is a small winding or coil 53 having a low impedance. The coil 53 may be supported in place by a fibrous or other similar plate 55 to which it is cemented 65 and which, in turn, is carried by the studs 57 on the plate 5. The coils 51 and 53 are preferably serially connected, as shown in Fig. 4, with their free ends or leads 59 and 61, respectively, connected to the terminals 63 and 65 on a terminal block 67 from which connection may be made to an external amplifying circuit. The circuit comprising the windings 51 and 53 is also provided with a lead 69 at the junction point 71 of the two coils, the lead 69 being connected to a terminal 73 on the terminal block 67.

It will be obvious, therefore, that by connecting an external amplifying circuit to the terminals 63 and 73, the output of the high impedance coil 51 may be employed; by connecting an external amplifying circuit to the terminals 65 and 73, the output from the low impedance coil 53 may be utilized; and by connecting the external amplifying circuit to the terminals 63 and 65, a very high impedance pick-up is provided and the combined output from both coils may be utilized. Inasmuch as the armature 37 is very short and light and has a low moment of inertia about its vibratory axis 35, it will be effective to reproduce high frequency sounds with great fidelity. At the same time, by reason of the greatly enlarged winding space, use may be made of both windings to reproduce the lower frequencies with great fidelity. Thus a pick-up device constructed according to my present invention will reproduce very efficiently sounds covering a very wide range 20 of the audio spectrum.

As noted heretofore, the device may be mounted on a suitable suspension arm and the terminals 63, 65 and/or 73 may be fitted to suitable corresponding terminals on the suspension arm to operate either as a low impedance pick-up, a very high impedance pick-up, or a pick-up of intermediate impedance. The slot 9 in the needle guide 7 is aligned with the needle socket 43 to permit easily inserting a needle in the socket from the top, it being merely necessary to insert the needle into the slot 9 and permit it to drop through the socket 43 onto an indexing device of the type described in my copending application Serial No. 187,935, filed Jan. 31, 1938, after which the screw 45 is tightened against the needle.

Although I have shown and described but a single embodiment of my invention, it will be apparent to those skilled in the art that many modifications thereof and changes therein are possible. I therefore desire that my invention shall not be limited except insofar as is made necessary by the prior art and by the spirit of the appended claims.

I claim as my invention:

1. In an electrical signal translating device, the combination of a supporting member, a stationary armature carried by said supporting member, and a vibratory armature pivotally carried by said stationary armature.

2. In an electrical signal translating device, the combination of a supporting member, a relatively long stationary armature carried by said supporting member, and a relatively short vibratory armature pivotally carried by said stationary armature, said short armature having a low moment of inertia about its vibratory axis.

3. In an electrical signal translating device, the combination of a supporting member, a stationary armature carried by said supporting member, a vibratory armature pivotally carried by said stationary armature, and separate voltage generating means associated with each of said armatures.

4. In an electrical signal translating device, the combination of a supporting member, a stationary armature carried by said supporting member, a vibratory armature pivotally carried by said stationary armature, a winding of relatively high impedance associated with said stationary armature, and a winding of relatively low impedance associated with said vibratory armature.

5. The invention set forth in claim 4 characterized in that said windings are connected in

series and characterized further in that the circuit comprising said windings includes a lead connected to the junction point of said windings whereby the outputs of either of said windings or the combined outputs of both of said windings may be utilized.

5. In an electrical signal translating device, the combination of a supporting member, a stationary armature carried by said supporting member, a vibratory armature pivotally carried by said stationary armature, and magnetic structure providing two separate pairs of pole pieces, each pair of pole pieces having an air gap therebetween, said stationary armature terminating in 10 one of said air gaps and said vibratory armature having its active end in the other of said air gaps.

6. In an electrical signal translating device, the combination of a supporting member, a stationary armature carried by said supporting member, a vibratory armature pivotally carried by said stationary armature, a magnetic structure providing two separate pairs of pole pieces, each pair of pole pieces having an air gap therebetween, said stationary armature terminating in 15 one of said air gaps and said vibratory armature having its active end in the other of said air gaps, and means constantly tending to hold said vibratory armature centered in its air gap.

7. In an electrical signal translating device, the combination of a supporting member, a stationary armature carried by said supporting member, a vibratory armature pivotally carried by said stationary armature, a magnetic structure providing two separate pairs of pole pieces, each pair of pole pieces having an air gap therebetween, said stationary armature terminating in 20 one of said air gaps and said vibratory armature having its active end in the other of said air gaps, and means constantly tending to hold said vibratory armature centered in its air gap.

8. The invention set forth in claim 6 characterized by the addition of means for individually adjusting the pole pieces of each pair relative to one another whereby said air gaps may be varied.

9. The invention set forth in claim 6 characterized in that one pair of pole pieces is located 35 on one side of said supporting member and the other pair of pole pieces is located on the other side of said supporting member, and characterized further in that said stationary armature extends through said supporting member but has 40 its major portion extending on said first named side, and said vibratory armature is located on said second named side.

10. In an electrical signal translating device, the combination of a supporting member, a stationary armature carried by said supporting member and extending therethrough with its major portion lying on one side of said supporting member, a vibratory armature pivotally carried by said stationary armature on the other side of said supporting member, and magnetic structure providing two separate pairs of pole pieces, one of said pairs of pole pieces lying on the first named side of said supporting member and the other lying on the second named side of said supporting member and each pair of pole pieces having an air gap therebetween, said stationary armature terminating in the air gap between said first named pair of pole pieces and said vibratory armature having its active end in the air gap between said other pair of pole pieces.

11. In an electrical signal translating device, the combination of a supporting member, a stationary armature carried by said supporting member and extending therethrough with its major portion lying on one side of said supporting member, a vibratory armature pivotally carried by said stationary armature on the other side of said supporting member, magnetic structure providing two separate pairs of pole pieces, one 65 of said pairs of pole pieces lying on the first named side of said supporting member and the

other lying on the second named side of said supporting member and each pair of pole pieces having an air gap therebetween, said stationary armature terminating in the air gap between said first named pair of pole pieces and said vibratory 5 armature having its active end in the air gap between said other pair of pole pieces, a relatively high impedance winding surrounding said stationary armature and located in the space between said supporting member and said first 10 named pair of pole pieces, and a relatively low impedance winding surrounding said vibratory armature and located in the space between said supporting member and said other pair of pole pieces.

12. The invention set forth in claim 11 characterized in that said windings are serially connected and characterized further in that the circuit comprising said windings is provided with a lead at the junction point of said windings where- 15 by the outputs of either of said windings or their combined outputs may be utilized.

13. In an electromagnetic signal translating device, the combination of means providing a source of magnetic flux, a pair of pole pieces having 20 transversely extending slots therein carried by said means, said pole pieces lying in a common plane and being physically separated from each other to provide an air gap therebetween, and a pair of screws mounted on said flux providing 25 means for movement axially in a plane parallel to that of said pole pieces and having heads thereon received within the slots in said pole pieces, said screws being so arranged on said flux providing means that movement thereof axially will 30 cause said pole pieces to move either toward or away from each other in their own plane whereby to vary the size of said air gap.

14. The invention set forth in claim 1 characterized in that said supporting member is formed 40 of non-magnetic material, and characterized further in that said armatures are both formed of magnetic material.

15. In an electrical signal translating device, the combination of means providing a magnetic 45 circuit and including two air gaps, a stationary armature having a portion located in one of said air gaps, and a movable armature associated with said stationary armature, said movable armature having a portion located in the other of said air 50 gaps.

16. In an electrical signal translating device, the combination of means providing a magnetic circuit and including two air gaps, a stationary armature having a portion located in one of said 55 air gaps, and a movable armature associated with said stationary armature, said movable armature having a relatively small moment of inertia and having a portion located in the other of said air gaps.

17. In an electrical signal translating device, the combination of means providing a magnetic circuit and including two air gaps, a stationary armature having a portion located in one of said air gaps, a high impedance winding surrounding 65 said stationary armature, a movable armature associated with said stationary armature, said movable armature having a portion located in the other of said air gaps, and a low impedance winding surrounding said movable armature.
